UNDERGARMENT

Harry Van Praag, New York, N. Y.

Application April 25, 1936, Serial No. 76,451

5 Claims. (Cl. 2—43)

The present invention relates to an undergarment and, more particularly, to a form-fitting girdle of elastic material provided with a crotch-piece. The invention is also concerned with the construction of the crotch-piece.

One object of the present invention is to provide a form-fitting girdle with a crotch-piece secured to the inside of the girdle at the lower back and front portions thereof.

Another object of the invention is the provision of a form-fitting girdle with a crotch-piece having one or both ends thereof detachably secured to the inside of the girdle.

A further object of the invention is to provide an elastic form-fitting girdle with an inwardly disposed crotch-piece attached thereto in such manner as not to interfere with the stretching of the girdle about the wearer.

Another object of the invention is to provide a crotch-piece of such construction and to attach the same in such manner as to prevent the formation of any bulges in the girdle at those portions to which the crotch-piece is attached.

A further object of the invention is to provide a crotch-piece which, together with the girdle, forms elastic thigh-encircling portions.

A further object of the invention is to provide a girdle having a detachable crotch-piece secured thereto in such manner as to afford maximum comfort to the wearer and, more particularly, to attach the crotch-piece in such manner as to avoid any discomfort to the wearer by reason of the detachable securing means at the lower back portion of the girdle.

A yet further object of the invention is generally to provide a form-fitting girdle having a crotch piece of simple construction and wholly or partially detachably secured in position on the inside of the girdle in such manner as to afford the wearer maximum comfort.

The above objects of the invention and other objects ancillary thereto will best be understood from the following description considered with reference to the accompanying drawing forming a part of the present specification.

In the drawing:

Fig. 1 is a front view of the girdle provided with a crotch-piece and constructed in accordance with the present invention;

Fig. 2 is a front view, on an enlarged scale, of the lower portion of the girdle with the crotch-piece removed and a part of the girdle cut away for the purposes of illustration;

Fig. 3 is a plan view of the crotch-piece; and

Fig. 4 is a perspective view of the girdle and the

crotch-piece secured thereto, illustrating the approximate form of the girdle and the crotch-piece as worn.

Referring to the drawing in detail, the girdle 10 may comprise any of the well known form-fitting girdle constructions and may be made of relatively heavy knit elastic material or of any other suitable fabric. Said girdle is provided with a crotch-piece 12 which, as here shown, is disposed inwardly of the girdle and extends from the back to the front thereof. Said crotch-piece may be made of any suitable material but is preferably constructed of comparatively light knit fabric. The crotch-piece is cut from said knit material so that it is elastic in a direction extending between the front and back of the girdle when the crotch-piece is secured in position. The edges of the crotch-piece extending in said direction are bound with narrow elastic tapes 14 secured by conventional extensible and contractible stitching 16.

In accordance with the present invention, provision is made for detachably securing the crotch-piece to the inside of the girdle at the front and back thereof. For this purpose, the front and rear edges of the crotch-piece are provided with fastener elements 18 and 19 secured to woven tapes or edgings 20. As here shown, said fastener elements are male snap fastener elements which are supplied as a commercial article for use in the garment industry on inextensible woven fabric strips or tapes in a manner well known to those skilled in this art. Tape portions 22 carrying the snap fastener elements 18 and 19 are stitched to the edge 20 at the front of the crotch-piece 12, while at the rear edge of said crotch-piece the edging tape 20 may consist of the tape which carries the fastener elements 18.

The crotch-piece, when attached to the girdle and when on the body of the wearer, is intended to assume the position illustrated in Fig. 4. Accordingly, provision is made for attaching the crotch-piece to the girdle so that the crotch-piece will assume said position. For this purpose, companion separable fastener members are attached to the inside of the girdle at the front and back thereof. Thus, as here shown, female snap fastener elements 24 carried by snap fastener tape portion 25 are secured adjacent the lower edge of the back of the girdle, said tape portion being preferably stitched to said edge portion of the girdle. At the front of the girdle, companion female snap fastener elements are secured to the inside of the girdle in such vertically and horizontally spaced relation that the crotch-piece 12, 55

when attached, assumes the position illustrated in Fig. 4. Thus, as best shown in Fig. 2, two female snap fastener elements 26 are attached to the girdle by means of tape portions 28 above the lower edge of the girdle, and at said edge 5 female snap fastener elements 30 are attached by means of the fastener tape portions 32. The upper fastener elements 28 and the lower fastener elements 30 are in spaced relation with respect to 10 each of the lower fastener elements, being more widely spaced from each other than the upper elements.

In attaching the crotch-piece to the girdle, the fastener elements 18 on the rear edge are engaged 15 with the fastener elements 24 at the back of the girdle, and the intermediate and end fastener elements 19 and 18 on the front edge are engaged with the upper and lower fastener elements 28 and 30, respectively, at the front of the girdle. 20 It will be observed that the crotch-piece is attached to the girdle in such manner that it does not interfere with the elasticity or extensibility thereof circumferentially of the wearer. For this purpose, the upper female snap fastener elements 28 are disposed in spaced relation and the intermediate companion snap fastener elements 19 at the front edge of the crotch-piece 12 are 25 more widely spaced than said snap fastener elements 28, thereby providing a slack portion in the front edge portion of the crotch-piece which can be taken up as the girdle stretches when put 30 on the wearer. The amount of slack provided, preferably, is such as can be entirely taken up between the upper fastener elements when the 35 girdle is worn so as to avoid any bulging of the girdle or of the material on the inside thereof. It will also be observed that by reason of the width of the front edge of the crotch-piece and the arrangement of the fastener elements thereon and on the front of the girdle, there is a transversely folded and slack portion in the crotch-piece when the latter is attached to the girdle. 40 This permits the lower front portion of the girdle to stretch and contract without hindrance by the crotch-piece. When the crotch-piece is in position and the girdle is worn, the elastic side edges 14 of the crotch-piece cooperate with the adjacent lower peripheral edge portions 34 of the girdle to form thigh-encircling portions which 45 are extensible and, therefore, provide substantial comfort to the wearer. The rear edge portion of the crotch-piece is relatively narrow and hence 50 the snap fastener elements do not occasion any discomfort to the wearer.

55 Thus, it is seen that the construction herein shown and described is well adapted to accomplish the several objects of the present invention. It will be understood, however, that the invention is capable of embodiment in other constructions, and that certain changes may be made in the construction herein shown and described without departing from the spirit of the invention. Therefore, I do not wish to be limited to the present disclosure except as may be required 60 by the appended claims considered with reference to the prior art.

Having thus described my invention, what I claim and desire to secure by Letters Patent of the United States is:

70 1. A circumferentially-elastic girdle of form-fitting construction, said girdle having a circumferentially continuous lower edge, a crotch-piece therefor adapted to extend from the back of the girdle to the front thereof, and companion fastener elements on said crotch-piece and on the

inner side of the girdle, respectively, at the front and back thereof for detachably securing said crotch-piece in position in the inside of the girdle, the rear edge of said crotch piece being positioned horizontally at the back of the girdle adjacent the lower edge thereof and the front edge of the crotch piece being secured to the front of the girdle at horizontally and vertically spaced points, the crotch piece, when the girdle is worn, having a horizontally positioned rear and intermediate part and a front part which extends upwardly from said intermediate part.

2. A circumferentially-elastic girdle of form-fitting construction, a crotch-piece therefor adapted to extend from the back of the girdle 15 to the front thereof, and companion fastener elements on said crotch-piece and on the inner side of the girdle, respectively, at the front and back thereof for detachably securing said crotch-piece in position on the inside of the girdle, the fastener elements at the front of the girdle including horizontally and vertically spaced elements at the lower edge of the girdle and said crotch-piece having similarly spaced companion elements whereby when said edge of the crotch piece is attached to said edge of the girdle, said crotch piece having an intermediate slack front edge portion to permit stretching of the lower edge portion of the girdle between said horizontally spaced elements, the rear edge of said crotch piece being 25 positioned horizontally at the back of the girdle adjacent the lower edge thereof and the front edge of the crotch piece being secured to the front of the girdle at horizontally and vertically spaced points, the crotch piece, when the girdle is worn, 30 having a horizontally positioned rear and intermediate part and a front part which extends upwardly from said intermediate part.

3. A circumferentially-elastic girdle of form-fitting construction, said girdle having a circumferentially continuous lower edge, a crotch-piece therefor adapted to extend from the back of the girdle to the front thereof, said crotch-piece having a narrow rear edge and a wider front edge, and means for detachably securing said front and rear edges of said crotch-piece to the front and back lower girdle portions, respectively, said means for securing the front edge of the crotch-piece to the front of the girdle comprising vertically and horizontally spaced fastener elements 40 attached to the inside of the front lower portion of the girdle above said lower edge, the front lower edge portion of said girdle between said lower fastener elements being free from attachment to said crotch piece whereby to permit stretching of said girdle portion, said crotch piece, when the girdle is worn, having a horizontally positioned rear and intermediate part and a front part which extends upwardly from said intermediate part.

4. A circumferentially-elastic girdle of form-fitting construction, said girdle having a circumferentially continuous lower edge, a crotch-piece therefor adapted to extend from the back of the girdle to the front thereof above said edge, said crotch-piece being extensible in the direction extending between the front and back of the girdle, elastic tapes secured to the side edges of said crotch-piece, inextensible tapes on the front and rear edges of said crotch-piece, and means securing said front and rear edges to the front and back, respectively, of the girdle, said crotch-piece, when the girdle is worn, having a horizontally positioned rear and intermediate part and 70

a front part which extends upwardly from said intermediate part.

5. A circumferentially-elastic girdle of form-fitting construction, said girdle having a circumferentially continuous lower edge, a crotch-piece therefor adapted to extend from the back of the girdle to the front thereof, said crotch-piece being extensible in the direction extending between the front and back of the girdle, elastic tapes secured 10 to the side edges of said crotch-piece, inextensible tapes on the front and rear edges of said crotch-piece, and means for detachably securing said crotch-piece to the girdle comprising companion

separable fastener elements on the front and rear edges of the crotch-piece and on the front and back, respectively, of the girdle, the rear edge of said crotch-piece being positioned horizontally at the back of the girdle adjacent the lower edge 5 thereof and the front edge of the crotch-piece being secured to the front of the girdle at horizontally and vertically spaced points, the crotch-piece, when the girdle is worn, having a horizontally positioned rear and intermediate part and a 10 front part which extends upwardly from said intermediate part.

HARRY VAN PRAAG.
